ARTHUR E. SANDERSON, OF SAN PEDRO, CALIFORNIA, ASSIGNOR OF ONE-HALF TO
HUGHES T. RUPERT, OF SAN PEDRO, CALIFORNIA

GARMENT RACK

Application filed March 16, 1931. Serial No. 523,082.

My invention relates to and has for a purpose the provision of a garment rack structurally characterized in such manner as to enable a large number of garments to be supported and compactly stored in a shallow closet or other restricted space without wrinkling or disarranging the garments, all while permitting garments to be applied to and removed from the rack with the utmost 10 ease and dispatch.

It is a further purpose of my invention to provide a garment rack of the above described character embodying a head gear supporting member which is associated with the rack in such manner as to effectively support one or more hats against displacement during manipulation of the rack.

I will describe only one form of garment rack embodying my invention, and will then 20 point out the novel features thereof in claims.

In the accompanying drawings:

Figure 1 is a view showing in side elevation one form of garment rack in applied position in a restricted space.

Figure 2 is an enlarged view of the garment rack in side elevation and illustrating the position occupied by the rack when applying or removing garments.

Figure 3 is a plan view of the garment rack 30 shown in Figure 2.

Figure 4 is a view of the garment rack in front elevation, and,

Figures 5 and 6 are fragmentary views 35 similar to Figure 2 but showing other and respectively different positions occupied by the garment rack during manipulation thereof.

Referring specifically to the drawings in which similar reference characters designate 40 similar parts in each of the several views, my invention in its present embodiment comprises a bracket B in the form of a sheet metal plate which is adapted to be secured to a wall, door or other vertical support by fastening 45 members 10 passing through suitable openings in the bracket. The bracket is provided with a pair of spaced apart ears 11 and 12, and a pin 13 is extended through the ears and through a garment supporting member 50 M at one end of the latter to mount the mem-

ber between the ears for pivotal movement vertically about the axis of the pin when the bracket is applied to a support as shown in Figures 1, 2, 5, and 6, so that the member can be swung manually in a plane at a right angle 55 to the plane of the support to occupy the various positions shown in these figures.

The garment supporting member is in the form of an arm constructed of sheet metal bent into L cross section to provide a side 60 flange 14 and a top flange 15, the former of which is provided with a series of slots 16 through which the hooks of conventional garment hangers can be extended to support a large number of hangers transversely of the 65 arm at intervals along its length.

Above the ears 11 and 12, the bracket B is provided with a single ear 17 to which is pivotally connected by means of a pin 18, one end of a latching member L in the form of a flat 70 metal bar. The opposite end of the latching member is provided with a laterally projecting latching lug 19 which during raising and lowering movements of the garment supporting member M, rides upon the top surface 20 75 of the flange 15 of the latter.

Pivoted by means of a pin 21 on an ear 22 upstruck from the side flange 14 of the garment supporting member M intermediate its ends, is a keeper K in the form of 80 a pawl tapered to a point from its pivoted end to its free end which latter normally rests under the action of gravity on the top surface 20 of the flange 15 and is directed towards the pivoted end of the garment supporting member.

The keeper is disposed in the path of movement of the lug 19 and its top edge inclined 85 upwardly to its pivoted end to provide a cam surface 23 leading to a notch 24 in said top edge of the keeper adapted to receive the lug. The position of the keeper along the length of the garment supporting member is such that as the latter approaches a horizontal position during its raising movement, the lug 19 will ride up the cam surface 90 95 23 and will gravitate into the notch 24 when the garment supporting member reaches horizontal position so that the latching member and keeper will co-act to releas- 100

ably retain the garment supporting member in horizontal position against the action of gravity.

It will be noted that the pivoted end of 5 the keeper K is spaced from the top surface 20 of the flange 15 so that upon raising the garment supporting member above horizontal position a sufficient amount for the lug 19 to leave the notch 24 and ride off of the 10 keeper onto the top surface 20 beyond the pivoted end of the keeper as shown in Figure 5, the lug will then be free to pass between the top surface and the keeper upon lowering movement of the garment supporting member under the action of gravity 15 as shown in Figure 6, thus releasing the garment supporting member from the latching member, and enabling the former member to move to the downwardly inclined position shown in full lines in Figure 1.

The latching member L is provided adjacent the lug 19, with a depending extension 25 which projects freely through a longitudinal slot 26 in the top flange 15 of the 25 garment supporting member M, and is split and bent laterally at its free end to provide a head 27. By the provision of this headed extension, the latching member is maintained connected to the garment supporting member, while permitting sufficient pivotal movement of the former relative to the latter, for the lug 19 to ride up over the keeper as previously described.

The garment rack also embodies a headgear 35 supporting member H in the form of a length of stiff wire bent into substantially T form to provide a vertical branch 28 and a horizontal branch 29 the free extremities of which are upturned to form pegs 30 on which 40 hats are adapted to be placed.

The lower end of the vertical branch 28 is pivotally connected by a pin 31 to the garment supporting member M adjacent its pivoted end, and the vertical branch is looped 45 intermediate its ends to provide an eye 32 to which is pivotally connected one end of a link 33, the opposite end of which is pivotally connected at 34 to the ear 17 of the bracket B, to the end that the headgear supporting member will be maintained substantially upright irrespective of the vertical position of the garment supporting member, to the end of preventing displacement of the hats from the former member.

55 The operation of the garment rack is as follows:

Let it be assumed that the garment rack is applied to a rear wall W of a shallow closet C, the door opening to which is controlled by a door D all as shown in Figure 1. With the door open, the garment supporting member M is free to occupy horizontal position and to project through the door opening as shown in broken lines in 65 this figure. With the member M latched in

its horizontal position, garment carrying hangers can be applied to and removed from the rack as desired. In order to close the door, and assuming that the rack is filled to capacity with garments, the garment supporting member M is first grasped and raised to the position shown in Figure 5 to release the latching member L from the keeper K, after which the member M is permitted to swing downwardly until the garments rest 75 against each other and the wall, thereby limiting the lowered position of the member M.

The garments will thus be compactly stored by the rack in a manner to prevent wrinkling or disarrangement of the garments as has been amply proven in practice, as the extent to which the member M in its downwardly inclined position, projects from the wall, is less than the depth of the closet, the door can now be closed. In order to render the garments accessible for removal from the rack, it is only necessary after the door has been opened, to raise the garment supporting member M until it is automatically latched in horizontal position by the co-acting latching member and keeper.

Although I have herein shown and described only one form of garment rack embodying my invention, it is to be understood that various changes and modifications may be made therein without departing from the spirit of the invention and the spirit and scope of the appended claims.

I claim as my invention:

1. A garment rack comprising a garment supporting member, means for mounting said member on a support for pivotal movement vertically to occupy raised and lowered positions, a pivoted latching member having a lug adapted to ride upon a surface of the garment supporting member during movement of the latter, and a keeper pivoted on the garment supporting member over which said lug is adapted to ride during raising movement of the garment supporting member, the keeper having a notch receiving said lug to latch the garment supporting member in raised position.

2. A garment rack comprising a garment supporting member, means for mounting said member on a support for pivotal movement vertically to occupy raised and lowered positions, a pivoted latching member having a lug adapted to ride upon a surface of the garment supporting member during movement of the latter, and a keeper pivoted on the garment supporting member over which said lug is adapted to ride during raising movement of the garment supporting member, the keeper having a notch receiving said lug to latch the garment supporting member in raised position, and the pivoted portion of the keeper being clear of said surface of the garment supporting member to enable the lug to pass between the sur-

face and the keeper during lowering movement of the garment supporting member following raising of the latter above said raised position a sufficient amount for the lug to ride off of the keeper.

3. A garment rack comprising a garment supporting member, means for mounting said member on a support for movement vertically to occupy a horizontal position for the application and removal of garments, and a downwardly inclined position under the weight of the garments so as to compactly store the garments one against another, means for releasably retaining the member in horizontal position, and means whereby the last means is caused to release said member for movement to the second mentioned position, upon elevating the member a predetermined amount above horizontal position.

4. A garment rack comprising a garment supporting member, means for mounting said member on a support for movement vertically to occupy a horizontal position for the application and removal of garments, and an inclined position to compactly store the garments one against another, means for releasably retaining said member in one of said positions, a headgear supporting member movably mounted on the hanger supporting member, and means for maintaining the headgear supporting member in a substantially upright position irrespective of the position occupied by the garment supporting member.

5. A garment rack comprising a bracket adapted to be secured to a support, a garment supporting arm pivoted on the bracket for movement vertically, a latch bar pivotally connected to the bracket and provided with a latching lug, and a keeper pivoted on the arm and provided with a notch receiving the lug to latch the arm in a predetermined position against the action of gravity.

45 6. A garment rack comprising a bracket adapted to be secured to a support, a garment supporting arm pivoted on the bracket for movement vertically, a latch bar pivotally connected to the bracket and riding upon a surface of the arm during pivotal movement of the arm, a keeper pivoted on the arm with the pivoted portion of the keeper clear of said surface and its free end resting on the latter so as to enable the latch bar to ride over the keeper during raising movement of the arm, and co-acting means on the latch bar and keeper for retaining the arm in a predetermined position against the action of gravity.

60 7. A garment rack comprising a bracket adapted to be secured to a support, a garment supporting arm pivoted on the bracket for movement vertically, a latch bar pivotally connected to the bracket and having a lug riding upon a surface of the arm during

pivotal movement of the latter, a keeper having a cam surface and pivoted on the arm with the pivoted portion of the keeper clear of said surface and its free end resting on the latter to enable the latch bar to ride over the cam surface of the keeper and pass the latter during raising movement of the arm and to pass between the keeper and said top surface during lowering movement of the arm, the cam surface of the keeper having a notch receiving the lug during raising movement of the arm to latch the latter against lowering movement.

8. A garment rack comprising a bracket adapted to be secured to a support, a garment supporting arm pivoted on the bracket for movement vertically, a latch bar pivotally connected to the bracket, means on the arm and bar co-acting to releasably retain the arm in a predetermined position against the action of gravity, a headgear supporting member pivoted on said arm, and means operatively connected to said member to maintain the latter in substantially upright position irrespective of the vertical position of the arm.

9. A garment rack comprising a bracket adapted to be secured to a support, a garment supporting arm pivoted on the bracket for movement vertically, a latch bar pivotally connected to the bracket, means on the arm and bar co-acting to releasably retain the arm in a predetermined position against the action of gravity, a headgear supporting member pivoted on said arm, and a link pivotally connected to the bracket and said member for maintaining the latter substantially upright irrespective of the vertical position of the arm.

10. A garment rack comprising a garment supporting member, means for pivotally mounting said member for movement vertically, a head gear supporting member movably mounted on the garment supporting member, and an operative connection between the headgear supporting member and a fixed support by which the headgear supporting member is maintained in a substantially upright position irrespective of the vertical position of the garment supporting member.

11. A garment rack comprising a garment supporting member mounted for pivotal movement vertically to occupy raised and lowered positions; a latching member connected to a support and riding upon a surface of the garment supporting member during movement of the latter; and a keeper on the garment supporting member, onto which the latching member rides from said surface of the garment supporting member during raising movement of the latter, for co-action with the latching member in latching the garment supporting member in raised position.

12. A garment rack comprising a garment supporting member mounted for pivotal

movement vertically to occupy raised and lowered positions; a latching member connected to a support and riding upon a surface of the garment supporting member during movement of the latter; and a keeper pivoted on the garment supporting member, onto which the latching member rides from said surface of the garment supporting member during raising movement of the latter, for co-action with the latching member in latching the garment supporting member in raised position, the pivoted portion of the keeper being clear of said surface to enable the latching member to pass between the surface and the keeper during lowering movement of the garment supporting member following raising of the latter above said raised position a sufficient amount for the latching member to ride off the keeper.
